UNITED STATES PATENT OFFICE.

GUY K. CLARK, OF CANON CITY, COLORADO.

MOTOR ATTACHMENT.

1,074,695.

Specification of Letters Patent.

Patented Oct. 7, 1913.

Application filed November 23, 1911. Serial No. 662,015.

To all whom it may concern:

Be it known that I, GUY K. CLARK, a citizen of the United States, residing at Canon City, in the county of Fremont and 5 State of Colorado, have invented a new and useful Motor Attachment, of which the following is a specification.

The present invention aims to provide mechanism for rewinding the film employed 10 in a moving picture machine, and to provide a novel means whereby the film may be wiped clean, as it passes from one reel to another.

With the foregoing and other objects 15 in view, which will appear as the description proceeds, the invention resides in the combination and arrangement of parts and in the details of construction hereinafter described and claimed, it being understood 20 that changes in the precise embodiment of invention herein disclosed can be made within the scope of what is claimed without departing from the spirit of the invention.

25 In the accompanying drawings, Figure 1 shows the invention in side elevation; Fig. 2 is a transverse section on the line 2—2 of Fig. 1.

The supporting structure embraces as a 30 primary element, a base 1, fixed to and rising from one end of which, is a standard 2. Secured to the opposite end of the base 1, is a receptacle 3, the same preferably comprising an outer box 4, ordinarily fashioned 35 from wood, the box 4 being lined, along its sides and upon its bottom, with a refractory material 5. This lining 5 may be fashioned from metal, asbestos or the like. The receptacle 3 is closed by a lid 6, hingedly 40 connected with the receptacle as shown at 7. The invention further includes an open, rectangular frame 9, one end of which is united by means of a securing member 11, with the standard 2, the other end wall of 45 the frame 9 being secured to the box 4. The motor 15, preferably electrically operated, is mounted within the receptacle 3. The lining 5 serves to prevent conflagration, resulting 50 from an improper operation of the motor 15. The invention further includes spaced primary and secondary shafts, 20 and 21, respectively, the shafts 20 and 21 being mounted for rotation in the frame 9. Journaled 55 for free rotation upon the primary shaft 20 is a primary reel 31, a secondary

reel 32 being secured upon the secondary shaft 21.

The film which is wound about the reels 31 and 32, is denoted by the numeral 35.

Secured to one end of the secondary shaft 60 21 is a pulley 36, about which is trained a belt 37, extended through an opening 38 in the receptacle 3, the belt 37 being operatively connected with the motor 15. Fixed to the secondary shaft 21, and located between the pulley 36 and the frame 9, is a pinion 39, meshing into a pinion 40, secured to a winding shaft 41, journaled for rotation in the frame 9.

Mechanism is provided for cleaning the 70 film 35, as it passes from the primary reel 31 to the secondary reel 32. This mechanism comprises a rack, including, as most clearly shown in Fig. 2, a base 56, from the ends of which, upright arms 57 and 58 extend. The base 56 of the rack is notched to form seats 59, adapted to receive the side portions of the frame 9, as clearly shown in Fig. 2, and securing elements 60 are extended through the lower ends of the arms 75 57 and 58, into engagement with the side portions of the frame 9.

In their adjacent faces, and at their upper ends, the arms 57 and 58 are equipped with guides 61, the lower ends of which 80 constitute shoulders 62, which shoulders are located well above the axes of the shafts 20 and 21. Slidably mounted in the guides 61, and normally resting against the shoulders 62, is a lower clamp block 63. An upper clamp block 64 is mounted for sliding movement in the guides 61, above the lower clamp block 63. The meeting faces of the blocks 63 and 64 are rounded and over these rounded surfaces are secured resilient, yieldable facings 65, preferably fashioned from velvet or the like. Secured to the upper face of the upper clamp block 64 is a thrust block 66, adapted to receive the lower end of a screw 67, threaded into the intermediate portion of a latch bar 68, one end of which is pivoted as shown at 69 to the arm 57, the free end of the latch bar 68 having an opening, adapted to receive the upper end of the arm 59, there being a wing screw 105 71 threaded into the free end of the latch bar 68, the wing screw being adapted to engage the arm 58, to hold the latch bar 68 in place.

In practical operation, when the motor 15 110

is operated, the belt 37 will operate the pulley 36 and drive the secondary shaft 21, causing a rotation of the secondary reel 32, the reel 32 unrolling the film 35 from the primary reel 31. The operation of rewinding the film 35 may be carried forward with great rapidity, when the motor 15 is operated. The film 35, as it passes from one reel to the other, will move between the resilient facings 65 which are carried by the clamp blocks 63 and 64, any dust or other material which may have accumulated upon the film, being swept away by the facings 65. By adjusting the tension of the set screw 67, the relative positions of the bars 63 and 64, and consequently the pressure of the facings 65 against the film 35 may be adjusted. When it is desired to remove one or both of the clamp blocks 63-64, the screw 20 71 may be manipulated to set free the movable end of the latch bar 68, whereupon the latch bar may be swung upwardly upon its pivotal mounting 69, thus setting free the clamp blocks 63 and 64, so that the same 25 may be removed upwardly, out of the guides 61. As will be readily understood, the latch bar 68 may be employed as a manually operable lever, whereby the pressure exerted by the upper block 64 against the lower 30 block 63, may be increased, temporarily, to clean a length of film which is soiled by an unusually tenacious material. It is to be noted that the shoulders 62 are located above the axes of the shafts 21 and 20, and 35 thus as clearly shown in Fig. 1, the film 35 will be led off the upper portions of the rolls which the reels 31 and 32 carry. The intermediate portion of the film will, therefore, be depressed to a minimum extent, and

consequently the intermediate portion of the 40 film will not be bent sharply over the lower surface of the upper clamp block 64. Undue wear upon the film will thereby be avoided, only so much pressure as is necessary for cleaning, being applied by manipulating the set screw 67, or by manipulating the latch member 68 leverwise.

Having thus described the invention, what is claimed is:—

In a machine for winding and cleaning 50 moving picture films, a frame; reel holding shafts journaled in the frame; oppositely disposed arms fixed to and rising from the frame between the shafts, the arms being provided in their adjacent faces with guides; 55 a lower clamp bar slidable vertically in the guides and held against horizontal movement by the guides, the lower clamp bar being upheld by the lower ends of the guides; an upper clamp bar slidable in the 60 guides above the lower clamp bar and held against horizontal movement by the guides; yieldable facing upon the bars, between which the film is adapted to pass, a latch bar pivoted to one arm and coöperating 65 with the other arm; locking means for uniting the latch bar with said other arm; and a member adjustable in the latch bar, transversely of the latch bar, and adapted to engage the upper clamp bar to secure a co-operation between the facings.

In testimony that I claim the foregoing as my own, I have hereto affixed my signature in the presence of two witnesses.

GUY K. CLARK.
